UNITED STATES PATENT OFFICE.

FRANK L. DAILEY, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

SANITARY RECEPTACLE FOR DENTAL USE.

Application filed June 30, 1926. Serial No. 119,629.

My invention relates to dental appliances and the object thereof is to provide the dentist with a readily handled sanitary tray or receptacle for broaches, burrs, and various other articles of current use in the practice 5 of his profession.

In its simplest form, the invention embodies a permanent base and replaceable trays intended for single use and then to be 10 discarded, thus obviating the necessity of sterilizing the receptacle between patients. A distinct merit of the invention is that it provides for the sanitary support of instruments or articles of such length as to over- 15 hang the margin of the base, which is so constructed as to enable the immediate support or tray to conform to the overhang without the hazard of casual displacement.

In the annexed drawings,

20 Figure 1 is a perspective view of the assembly.

Fig. 2 illustrates the units in detached relation.

Fig. 3 is a sectional view of the base.

25 According to my invention, I provide a base 5 constructed of refractory material, as for example, glass, wood or metal, so as to be more or less permanent. The base 5 is of circular shallow cup form with a curved 30 or tapered rim 6 defining a receptacle 7 whose side wall is substantially perpendicular and roughened for a purpose hereinafter referred to. The base is provided with op-

posed marginal notches 8, affording finger grips, and with a radial passway or gap 9, 35 which latter serves the dual office of increasing the capacity of the receptacle and of facilitating the removal of the sanitary lining medium or tray.

The lining medium or tray may well be a 40 cupped disk 10 of paper designed to snugly fit the receptacle 7 of the base, the retention of the tray in the receptacle being promoted by giving its side wall an upward flare. Held thusly as well as by the roughened 45 wall of the receptacle, the area of the tray can be extended beyond the marginal limits of the receptacle 7 by molding it to the contour of the passway or gap 9. After single use the element 10 may readily be ejected 50 and replaced by a fresh one.

Having described my invention, I claim—

An appliance of the character stated, comprising a base having a cup portion to receive paper linings or trays, the side wall of 55 the cup having a gap, and a paper lining having a rim portion which may be molded to fit said gap, whereby dental implements may be sanitarily supported with their overhang in substantially the plane of the lining, the outer margin of the cup portion having opposed notches which constitute 60 grips.

In testimony whereof I affix my signature.

FRANK L. DAILEY.
